UNITED STATES PATENT OFFICE.

HENRY J. TRAUBEL, OF CRESSKILL, NEW JERSEY.

GAME DEVICE.

Application filed November 15, 1922. Serial No. 601,005.

To all whom it may concern:

Be it known that I, HENRY J. TRAUBEL, a citizen of the United States, residing at Cresskill, in the county of Bergen and State 5 of New Jersey, have invented certain new and useful Improvements in Game Devices, of which the following is a specification, reference being had to the accompanying drawing.

10 The invention relates to improvements in game devices, and has for its object a device for spinning a die, the purpose of which is to make a game of the sale of toys and other articles of merchandise, and in which 15 the scoring number determines the class of article sold. It is contemplated that the die used shall be, at least, fifteen inches in diameter and the device for spinning the same shall have proportions which shall be adequate for spinning such a die.

Figure 1 is a plan view;

Figure 2 a section on line 2—2 of Figure 1, and

25 Figure 3 is a diagrammatical view of the electrical wiring.

Referring to the drawings in detail, 1 represents a circular table, having supports, 2, strengthened by cross-braces 3. The circular table 1 has a side-wall or rim 4. A circular buffer rail 5 is preferably superposed above the rim 4, having supports 6. The buffer rail 5 is grooved, as at 7, for an insert of resilient material, such as rubber, as indicated at 8. Instead of the superposed 35 buffer rail 5, the side wall may be carried higher so as to hold the rubber insert.

The bottom of the table is provided with a central opening 9, in which is loosely mounted a pin or axle 10, the lower end of 40 the latter being secured in a suitable bearing on the cross-braces 3, as at 11. Upon the upper end of the pin or axle 10 is fixedly mounted a disc or spinner 12. Preferably, the disc 12 is wood and its surface roughened to cause frictional contact with the die resting thereon. On the lower end of the axle 10 is fixedly mounted a pulley 13, to be driven by the belt 14 running from the driving shaft 15 of the electric motor 16. The 45 table is ordinarily lighted by the two electric lamps 17 connected with wires running through tubular supports 18 attached to the table as at 19.

The die 20 is, in general, spherical but 55 having a multiplicity of flat faces 21. These faces are paired so that the faces of each

pair are diametrically opposite each other, and they have two purposes, one, being to bear a number, and the other to afford a frictional hold of the die with the spinner 60 so that it will be thrown therefrom with maximum force and sufficient to make it contact with the rubber of the buffer rail 5 and rebound and contact again with the spinner. This action of the die may be repeated several times before it comes to a stop, when the number uppermost will usually determine the class of merchandise or toy purchased. But another element is brought into the game by the occasional 70 illumination of the red lamp, indicated in the drawing at 22, the means for illuminating which will now be described.

On the driving shaft of the motor there is loosely mounted a non-rotatable disc 23, consisting of any suitable insulating material, and provided with contact points 24, connected to electric wires 25 which are connected to the red lamp 22 and to a source 75 of supply (not shown). Also fixedly 80 mounted on the driving shaft of the motor, and midway between its two ends, is a short arm or link 26, to one end of which arm is pivoted a lever 27, as at 28. The outer end of said lever 27 is yieldingly connected by 85 spiral spring 29 to the end of arm 26 as at 30. When the motor is in operation the centrifugal force exerted upon the lever arm 27 causes the latter to spread apart from the short arm 26, against the action of spring 90 29, so that its end is near the periphery of the disc 23, and, therefore, outside of the orbit in which the two contact points 24 are located, but, when the motor ceases to operate, the centrifugal force exerted upon the 95 lever arm 27 is lost and the latter is drawn inwardly by the spiral spring 29 so that the bridge piece 31 on the lever arm 27 now travels in the orbit of the contact points 24 and may possibly come to rest over the latter to close the electrical circuit and illuminate the red lamp 22, the happening of which is a coincidence that increases the reward to the player. A switch is provided 100 on the side of the table, as at 32, to start and stop the motor.

What I claim is:

1. The combination of a table, a spinner connected therewith, a motor for operating the spinner, an electric lamp, means for lighting the lamp, and automatic means interposed in the lamp circuit and connected 110

to said motor for opening and closing the circuit.

2. The combination of a table, a spinner connected therewith, a motor for operating the spinner, an electric lamp, means for lighting the lamp, and centrifugally operating means interposed in the lamp circuit for opening and closing the circuit.

3. The combination of a table, a spinner connected therewith, means for operating the spinner, an electric lamp, means for lighting the lamp, and automatic means including a rotatable bridge-piece interposed in the lamp circuit and connected to the means for operating the spinner for opening and closing the circuit.

4. The combination of a table, a spinner connected therewith, a motor for operating the spinner, an electric lamp, means for

lighting the lamp, and means interposed in the lamp circuit for automatically opening and closing the same, including an insulated stationary member provided with contact-points and a rotatable spring-pressed bridge-piece.

5. The combination of a table, a spinner connected therewith, a motor for operating the spinner, an electric lamp, means for lighting the lamp, and means interposed in the lamp circuit for automatically opening and closing the same, including an insulated stationary member provided with contact-points and a rotatable bridge-piece connected to said motor and adapted to occupy a position in the orbit of said contact-points when the motor is at rest and to expand out of said orbit when the motor is in operation.

HENRY J. TRAUBEL.
